UNITED STATES PATENT OFFICE

136,529

DESIGN FOR A MEDALLION OR THE LIKE

Carl L. Schmitz, New York, N. Y., assignor to Cartier, Inc., New York, N. Y., a corporation of
New York

Application August 7, 1943, Serial No. 110,851

Term of patent 7 years

To all whom it may concern:

Be it known that I, Carl L. Schmitz, a citizen of the United States of America, residing at New York city, in the county and State of New York, have invented a new, original, and ornamental Design for a Medallion or the like, of which the following is a specification, reference being had to the accompanying drawing, forming part thereof.

In the drawing:

I claim:

The ornamental design for a medallion or the like, as shown.

CARL L. SCHMITZ.
